Attorney.

UNITED STATES PATENT OFFICE

WOLDEMAR FEHRMANN, OF DRESDEN-STREHLEN, GERMANY

APPARATUS FOR DYEING AND WET-TREATING OF FABRIC

Application filed June 7, 1927, Serial No. 197,166, and in Germany February 15, 1925.

In order to accommodate fabrics, in such quantities as are to be dealt with in the wholesale manufacture, in the treating-tanks of the apparatus in which the liquid circulates, the fabrics must be brought into a compact form, and if treated in folded form, irregularities and the creases can not be avoided. It has long been recognized that the winding of the fabric around a perforated cylinder is most convenient. Experiments have however shown that the holes of the cylinder through which the dyeing liquid circulates cause in the layers of fabric color spots of the shape of the holes, and one has hitherto not succeeded in creating a cylinder, which permits of an absolute uniform distribution of the liquid over the entire cylinder surface. There was further no sufficient packing of the end faces of the roll of fabric so that at these ends a more intensive circulation of the bath at the variations of volume of the roll during the treatment is prevented.

This invention solves these problems by winding several layers of braided or woven wire around the portions of the material carrier which are permeable to the liquid, and consisting generally of perforated sheet metal. A thick cover is formed so that the liquid when traversing this cover is uniformly distributed. By making this cover from several layers, for instance thick-wire netting for the first layer, wire cloth for the middle-layer and wire-gauze for the surface of the cover, the said perforated sheet-metal can be interchanged against a coarse framework, or it can be quite omitted. Even when the volume of the roll of fabric alters during the treatment, a more easy passing of the liquid through the ends of the roll of fabric is prevented as by means of a spring or by a pressure of the liquid passing from the outer side through the roll of fabric a cap-disc is pressed onto the upper end face of a vertical roll of fabric and the lower end face of this roll of fabric is pressed against the bottom of the tank, a cap being arranged at the point of this bottom designed to receive the end of the cylinder projecting from the roll of fabric, or the end face of the roll

of fabric is pressed against a cap-shaped disc on the bottom plate of the tank.

An embodiment of the invention is shown, by way of example, in the accompanying drawing in which the only figure shows a longitudinal section of a carrier for fabrics mounted for use.

The cylinder, around which the fabric 1 to be treated is wound, consists of rods or laths 2, 3, which form together with the cylindrical end-pieces 4, 5 a reel and is covered by several superposed layers 6 first of coarse- and then of finer-meshed wire gauze. The lower end piece 5 has an aperture 7 through which the liquid circulates. On the bottom plate of the tank 8 a cap 9 is arranged designed to receive the end of the cylinder which projects from the roll of fabric 1. This cap is connected with the liquid tube 10; the other liquid tube 11 taps into the upper portion of the tank 8. Through the two liquid tubes liquid is conveyed by means of a pump or of any other forcing device in a manner known per se to or from the tank 8. The cap disc 12 is pressed against the upper end face of the roll of fabric 1 by a spiral spring 13 fixed on the lid of the tank, the lower end face of the roll of fabric being pressed against the bottom plate of the tank whereby both end faces of the roll of fabric are tightly packed independently of shortening or other alterations of volume during the wet-treatment at changing temperature.

The spring 13 might also be arranged outside the tank, the pressure of this spring being transferred by means of a rod traversing a stuffing box upon the lid of the tank, the tension of said spring being adapted to be regulated during the working by means of nuts. If the liquid is forced through the roll of fabric exclusively from the outer side inwards as indicated in the drawing by an arrow line, and if the diameter of the cylinder is not too short, the pressure difference of the liquid on the outer side and on the inner side of the roll of fabric is sufficient to securely hold the cap-shaped disk on the upper end face of the fabric and to press this roll of fabric at its lower end on the

bottom of the tank. In these cases the spring may be omitted.

The fabric is wound on the cylinder 2, 3 so that both ends of the cylinder project a similar distance. When the roll of fabric is shorter, i. e. narrower than shown on the drawing, the lower end 5 of the cylinder or the core of the roll projects deeper into the lower cap 9 and the upper end 4 of the cylinder or core projects deeper into the upper cap 12, this cap being lowered a greater distance on the upper end of the fabric roll either by the pressure of spring 13, or, when no spring is provided, by gravity and by the pressure of the liquid. By the height of the spring 13 pressure on the upper cap 12 can vary according to the height of the roll of fabric or the tension of the spring may be regulated accordingly. This material carrier can therefore be used for fabrics of different widths.

I claim:—

1. Apparatus for dyeing and wet treating of fabric by circulating liquid, comprising a tank with lid and having a hole in its bottom plate, means for circulating liquid through said tank, a cylinder permeable for liquid in said tank adapted to have a roll of fabric wound thereon the lower end of said cylinder projecting through said hole in the bottom plate of the tank and the whole inserted in the tank so that the roll of fabric rests at its lower end on the bottom of said tank, a cap on the bottom of the tank adapted to receive the lower end of said cylinder, a movable cap-shaped disc, resting on the upper end of said roll of fabric so that both end faces of said roll of fabric are protected against stronger flow of the liquid than at the middle part of the roll.

2. Apparatus for dyeing and wet treating of fabric by circulating liquid, comprising a tank with a lid and having a hole in its bottom plate, means for circulating liquid through said tank, a cylinder permeable for liquid in said tank adapted to have a roll of fabric wound thereon the lower end of said cylinder projecting through said hole in the bottom plate of the tank, a cover of several layers of braided or woven wire on said cylinder, the whole inserted in the tank so that the roll of fabric rests at its lower end on the bottom of said tank, a cap on the bottom of the tank adapted to receive the lower end of said cylinder, a movable cap-shaped disc, resting on the upper end of said roll of fabric so that both end faces of said roll of fabric are protected against stronger flow of the liquid than at the middle part of the roll.

3. Apparatus for dyeing and wet treating of fabric by circulating liquid, comprising a tank with lid and having a hole in its bottom plate, means for circulating liquid through said tank, a cylinder permeable for liquid

in said tank adapted to have a roll of fabric wound thereon the lower end of said cylinder projecting through said hole in the bottom plate of the tank, a cover of several layers of braided or woven wire on said cylinder, the whole inserted in the tank so that the roll of fabric rests at its lower end on the bottom of said tank, a cap on the bottom of the tank adapted to receive the lower end of said cylinder, a movable cap-shaped disc resting on the upper end of said roll of fabric, a spring resting on said cap-shaped disc and bearing against said lid of said tank, said spring pressing said cap-shaped disc against the upper end face of said roll of fabric and the latter against the bottom of the tank so that both end faces of said roll of fabric are protected against stronger flow of the liquid than at the middle part of the roll.

In testimony whereof I affix my signature.
WOLDEMAR FEHRMANN.
